FABRIC ENVELOPE COVERED METAL SHANK FOR SHOES

Herbert H. Roosa, Rochester, N. Y.

Application December 16, 1931. Serial No. 581,423

2 Claims. (Cl. 36—76)

My invention relates to an improvement in shoe manufacturing, and more particularly to an improvement in the shank portion of the shoe, and in the method of securing the shank in place, particularly in cement constructed shoes.

An object of my invention is to provide an economical and practical means of securely attaching metal shanks to shoes, between the inner soles and outer soles thereof.

10 A further object is to provide the metal shank with a suitable fabric covering or envelope which is cemented to and around the metal shank by a suitable adhesive cement, preferably a nitro-cellulose cement and in also providing excess fabric ends beyond the metal shank ends, which fabric ends make a firm cemented joint with the body of the insole and the outsole.

15 A further object is to permanently secure the fabric covered metal shank in place to the outer sole and to the insole, so that both outer and inner soles are permanently united by means of the fabric covering, and accordingly do not separate during the life of the shoe at the surfaces of union with the fabric covered metal shank.

20 A further object is to provide a shoe in which the fabric covered metal shank is practically integrally united with both inner and outer soles, thereby preventing squeaking during wear and also preventing the metal shank from cutting through either the inner or outer sole.

25 A further object is to provide a shoe in which the fabric covered metal shank having its outer surfaces coated with cement is secured to the inner sole and to the outer sole by the cement, thus providing a solid bond from edge to edge under the arch or shank of the shoe outsole so that during the wear of the shoe the outer sole does not separate from the body of the shoe at the shank portion.

30 A further object is to provide an increased area of contact cemented surface, thus forming a complete bond from edge to edge on the cemented surfaces of the shoe bottom at the shank portion thereof, and the surface of fabric covered metal shank, and outsole of the shoe, which bond permanently remains intact during wear.

35 A further object is to provide a shoe in which the outer and inner soles are so firmly cemented around the fabric covered or enveloped metal shank that all tendency for the metal shank to shift is prevented, thereby avoiding friction and destructive wear upon the inner and outer soles.

In the accompanying drawing,

40 Fig. 1 is an elevation of a cement constructed shoe, partly broken away, showing the shank

covered with a fabric covering and cemented between the inner and outer soles;

45 Fig. 2 is an enlarged longitudinal sectional view of a metal shank provided with a fabric covering envelope, the covering being cemented directly upon and around the metal shank, and also showing extending ends of the fabric covering which are cemented together, thereby completely enclosing the metal shank in the fabric covering.

50 Figs. 3 and 4 are section and plan views respectively, of one type of fabric covering or envelope, shown as a fabric tube, within which the metal shank is inserted and cemented;

55 Fig. 5 is a plan view, partly broken, of a metal shank provided with a suitable fabric covering, the fabric covering or envelope being shown as wrapped around the shank and cemented thereto;

60 Fig. 6 illustrates diagrammatically a view of a rear portion of a shoe insole having an inseam channel thereon to which the shoe upper is to be attached by means of an inseam; and showing the outer edges of a shank piece attached to the reverse side of the channelled insole by means of a suitable cement, and also showing the fabric covered metal shank in dotted lines secured in place between the channelled insole and the attached shank piece. The method of securing the fabric covered metal shank as herein illustrated 65 is also applicable to attaching shank pieces and fabric covered metal shanks in "turn" shoe construction.

70 In the various methods used in the manufacture of shoes in which metal shanks are employed, the metal shanks are placed between insoles and outsoles at the shank portions of the shoes, or between the shank piece and the outsole, or between the shank piece and the insole. The metal shank is usually secured to the insoles or to the shank pieces by tacks, rivets, staples, or other metal fastening means. In use, these fastening devices rust, and break from the insole or shank piece, thereby causing the metal shank to become loose, and allowing the metal shank to cut through the outsole, or through the insole, thereby rendering such shoe practically useless. Metal shanks have been directly cemented between the layers of the sole of the shoe in cement constructed shoes, but the cement does not permanently adhere to the metal surface, and in use, the layers of the sole separate from the metal shank, and continued walking develops a 75 flexing action at the shank portion which loosens 80

110

the outsole from the shoe between the ball and the breast of the shoe heel.

In the present invention, the metal shank 1, is suitably covered with a fabric 2, which fabric 5 may consist of a tube 3, in which the shank is placed, or a suitable strip of fabric for example, a ribbon or flat tape or cord 4 wrapped around the same. The metal surfaces of the shank are first 10 coated with a cement, preferably a nitrocellulose cement 10, and thereafter the fabric covering is applied either by inserting the metal shank into the braided or woven tube 3 shown in Fig. 4, or the shank may be wrapped or enveloped with the fabric strip 4 as shown in Fig. 5. While a covering 15 made of fabric is preferred, the covering may be made of thin leather or other soft porous material which will be impregnated with cement. After the shank is properly covered, the outer 20 surfaces of the covering are coated with a sufficient quantity of cement 11, and the ends 6 of the fabric are closed or pinched together as shown at 7 in Fig. 2. The shank is now completely sealed in the fabric covering and thereby rendered rust-proof. Any suitable type of cement may be used, 25 for example, nitrocellulose, rubber cement, or other suitable adhesive, preferably nitrocellulose cement.

The fabric covered or enveloped shank is now 30 coated all over with a cement 11, and that portion 8 of the shoe insole or shank piece 9 is also coated with the cement on its surface at which the fabric covered shank is to be positioned. The cement coated fabric covered metal shank is 35 immediately placed upon the cement coated portion of the insole or shank piece 9 of the shoe, and is temporarily held in place by a tack or tacks, which tacks are later removed when the cement has become sufficiently dry. From this 40 point on, the usual process of manufacture of shoes is followed according to the particular type of shoe construction method employed. The completed shoe has the fabric covered or enveloped metal shank permanently and immovably secured in place, and a permanent bond is effected between the fabric covering of the metal shank 45

and the adjacent surfaces in contact therewith.

During the normal life of the shoe the several 50 layers of insole 9, shoe upper lining 14, counter 13, shoe upper 15, and outsole 12, are permanently bonded together because of the integral union 80 of the shank piece or inner sole, or shank piece and outer sole to the fabric covering surrounding the metal shank.

The method described herein of covering or 85 enveloping metal shanks for shoes with a fabric covering or envelope is applicable to any style, shape, or size, of metal shanks used in the construction of footwear, and is not limited in its application solely to the particular type of shoe, or shape of metal shank, illustrated herewith. 90 In the claims, the word fabric is used to define any soft flexible porous material which may be impregnated with the cement, and form a permanent bond between the enclosed metal shank and the insole and outsole of a cement constructed shoe. 95

I claim:—

1. A metal shank stiffener for shoes, including an elongated body, and a flattened tube having continuous seamless walls of a material pervious 100 to cement and provided with a longitudinal opening receiving the elongated body and completely covering and concealing the same, the ends of the tube being extended beyond the ends of the body to form terminal cementing attaching portions 105 and collapsed and sealing the body within the tube.

2. A metal shank stiffener for shoes, including an elongated body, and a flattened tube having continuous seamless walls of woven fabric and provided with a longitudinal opening receiving the elongated body and completely covering the same, the ends of the tube being extended beyond the ends of the body to form attaching portions and the said tube being impregnated with cement 110 and the extended ends being collapsed and closing the ends of the longitudinal opening and sealing the body within the same. 115
